DESIGN FOR A FAN PROPELLER

Eugene Newnham, St. Louis, Mo., assignor to
Knapp-Monarch Company, St. Louis, Mo., a
corporation of Missouri

Application September 23, 1936, Serial No. 64,968

Term of patent 7 years

To all whom it may concern:

Be it known that I, Eugene Newnham, a citizen of the United States and a resident of the city of St. Louis and State of Missouri, have invented a new, original, and ornamental Design for a Fan Propeller, of which the following is a specification, reference being had to the accompanying drawing, forming part thereof.

Figure 1 is a front elevation of a fan propeller embodying my invention.

Figure 2 is a plan view thereof looking in the direction of the arrow 2 adjacent Figure 1; and

Figure 3 is a similar plan view looking in the direction of the arrow 3 adjacent Figure 1.

I claim:

The ornamental design for a fan propeller, as shown.

EUGENE NEWNHAM.
